UNITED STATES PATENT OFFICE.

II. CLAY BASCOM, OF TROY, AND TOBIAS S. HEISTER, OF LANSINGBURG, NEW YORK, ASSIGNEES TO OTIS G. CLARK AND DANIEL D. BUCKLIN, EXECUTORS OF THE LAST WILL OF N. S. VEDDER, DECEASED.

DESIGN FOR A GLOBE-STOVE.

SPECIFICATION forming part of Design No. 11,878, dated July 20, 1880.

Application filed June 14, 1880. Term of patent 3½ years.

To all whom it may concern:

Be it known that we, H. CLAY BASCOM, of the city of Troy, in the county of Rensselaer and State of New York, and TOBIAS S. HEISTER, of the village of Lansingburg, in said county and State, have jointly invented and produced a new and original Design for Globe-Stoves, of which the following is a specification, reference being had to the accompanying print or engraving of a stove having our said new design.

One feature of our invention is the design for the base section A, composed of the eight-sided bottom plate, B, having the front, back, and side edge faces, *c*, of greater length than the corner edge faces, *d*, the eight-sided lower top plate, E, having the front, back, and side edge faces, *f*, of greater length than the corner edge faces, *g*, and the intervening upright four-sided portion H, having the corners recessed with obtuse re-entering angles *i* and intermediate ornamented panels, *j*, the series of ornaments *k*, alternating with draft-apertures *l* in the front plate, the compound ornament *m* on the side plates, and the base molding *n*, all shaped and arranged together as represented in the aforesaid print.

Another feature is the design for the body section O, composed of the oval globe P, with

the conic frustums *q r s* at the top and bottom, 30 respectively, the octagonal center fender, T, having the flat inclined edges *u* and scroll-form open-work *v*, and the ornamented four-sided upwardly-tapering inclined side door, W, having the truncate upper corners, *x*, the 35 convex curve *y* in the top, and the two four-sided upwardly-tapering illumination-apertures *z*, with truncate upper corners only, all shaped, arranged, and combined as shown in the aforesaid engraving.

What we claim as our joint invention is—

1. The design for the lower section, A, composed of the parts B *c d*, E *f g*, and H *i j k l m n*, all shaped, arranged, and combined as described and shown.

2. The design for the body section O, composed of the parts P, *q r s*, T *u v*, and W *x y z*, all shaped, arranged, and combined as shown and described.

In testimony whereof we hereunto set our hands, in the presence of two subscribing witnesses, this 9th day of June, 1880.

H. CLAY BASCOM.
TOBIAS S. HEISTER.

Witnesses:

JAMES A. GILMAN,
CHESTER BASCOM.
